COLLAPSIBLE GATE

Arthur W. Cunningham, Dayton, Ohio

Application April 4, 1938, Serial No. 199,838

10 Claims. (Cl. 20—19)

This invention relates to a collapsible gate and is designed primarily for use with elevators. It is common practice to provide the doorways of elevator shafts, particularly the shafts of freight elevators, with vertically movable gates but these gates, for the most part at least, have been of such a character as to require a large overhead clearance to permit the gate to move to its upper or open position. In many buildings the ceilings of the rooms with which the elevator shaft communicates are so low that only a small overhead clearance is available, thus preventing the use of such a gate without making the same of such a narrow vertical width or height that it will not adequately close the doorway.

One object of the present invention is to provide a gate of such a character that when in its normal or closed position it will adequately close the doorway but which may be collapsed to a narrow width so that it will occupy a relatively small space above the doorway when moved to its open position.

A further object of the invention is to provide a gate comprising a plurality of sections which are so connected that they may be moved in unison and may also be moved with relation one to the other into overlapping positions.

A further object of the invention is to provide such a gate in which the sections may be quickly and easily moved into and out of their overlapping positions.

A further object of the invention is to provide such a gate with means for positively limiting the movement of the sections from their overlapping positions.

A further object of the invention is to provide such a gate with means for automatically accommodating the same to variations in the distance between upright guides.

A further object of the invention is to provide such a gate which will be of simple inexpensive construction and in which the various parts will be of such a character that they will not be easily disarranged so as to render the apparatus inoperative.

Other objects of the invention may appear as the apparatus is described in detail.

In the accompanying drawings Fig. 1 is an elevation of an installation embodying my invention, looking from the inside of the elevator shaft; Fig. 2 is a similar view showing the gate collapsed and in its elevated position; Fig. 3 is an enlarged section taken on the line 3—3 of Fig. 1; Fig. 4 is a detail view of the automatically adjustable slide block; Fig. 5 is a section taken

on the line 5—5 of Fig. 1, looking in the direction of the arrows; Fig. 6 is a section taken on the line 6—6 of Fig. 1, looking in the direction of the arrows; Fig. 7 is a section taken on the line 7—7 of Fig. 2; and Fig. 8 is a similar view showing the sections in their extended positions.

In these drawings I have illustrated one embodiment of my invention and have shown the same as installed in an elevator shaft having a doorway 10 and having on opposite sides of the doorway frame members or vertical posts 11 which are provided with upright guides, such as slide bars 12. The gate comprises a plurality of sections which are so connected one to the other that they may be moved in unison or may be moved with relation one to the other into overlapping positions so as to collapse the gate to a relatively narrow width. The gate comprises three sections 13, 14 and 15 and in the arrangement here shown the upper and lower sections 13 and 15 are movable with relation to the intermediate section 14 so that they may be brought into overlapping positions with relation thereto, it being understood that the three sections of the gate are arranged in separate but adjacent planes.

The several sections may be supported and connected one to the other in any suitable manner. In the particular construction illustrated elongate members 16 are secured to the respective ends 30 of the intermediate section 14 and are provided with means for slidably connecting the same with the upright guides 12. The elongate members may be of any suitable character and are preferably of such a length that they extend from 35 points near the upper edge of the intermediate section to points a substantial distance below the lower edge of that section. Each elongate member is here shown as formed of two angle irons 17 rigidly secured to the intermediate section 14 40 by straps 18 and having parallel flanges 19 extending inwardly in spaced relation to the straps to points spaced short distances from the outer ends of the gate sections. In the present construction each elongate member 16 is connected 45 with the intermediate gate section at two points and said intermediate section is provided at each end with a relatively narrow downwardly extending part 14' to which the lower straps 18 are secured, as shown in full lines in Figs. 2 and 6. 50 The means for slidably connecting the elongate members with the upright guides may take various forms and it is preferably of such a character as to automatically accommodate the gate to any minor variations in the distance between the two 55

laterally spaced upright guides. For this purpose each elongate member is provided with one or more supporting members, each member being here shown as comprising a pair of outwardly extending flanges or plates 20 rigidly secured to the elongate member and spaced apart to receive between them a slide block 21 having its outer edge grooved as at 22 to receive the edge of the adjacent slide bar 12. The supporting members 5 are provided with downwardly and outwardly inclined slots 23 and the slide block is provided with parts, such as pins 24, which extend into and are freely slideable in the slots 23 so that when unrestrained the slide block will move 10 downwardly and outwardly by gravity and when inward pressure is exerted upon the slide block it will move upwardly and inwardly. In this manner the slide blocks at the opposite ends of the intermediate section of the gate will automatically accommodate themselves to any variations in the distance between the slide bars 12. Cables 25 are connected with the respective elongate members 16, extend upwardly about pulleys 26 near the upper ends of the posts 11 and are 15 connected at their other ends with weights 27 which counterbalance the weight of the gate as a whole. In the arrangement shown each cable 25 extends between the straps 18 at the adjacent end of the intermediate section and is connected with a plate 28 secured to the lower edges 20 of those straps. (See Figs. 3 and 4.)

The lower gate section 15 is provided at each end with one or more slide blocks 29 which, in the present instance, are formed integral with 35 straps 30 rigidly secured to the respective ends of the gate section, each slide block having a groove 31 to receive the adjacent flange 19 of the elongate member 16, which forms a guide therefor. The upper gate section has at each end 40 thereof a downwardly extending part or arm 32 to which is rigidly secured a slide block 33 which is also grooved to receive the edge of the adjacent flange 19 of the elongate member. Secured to each end of the upper portion of the 45 upper section is an outwardly extending bent arm 34, shown in dotted lines in Fig. 3, which is provided with a slide block 35 grooved to receive the edge of the upright guide 12, so that this upper gate section is slidably connected both with the elongate members 16 and with the fixed 50 upright guides 12. By so mounting the upper and lower gate sections they may be moved simultaneously into positions alongside of the intermediate gate section.

55 The upper and lower gate sections may be connected with the elongate members 16 and the intermediate gate section 14 in any suitable manner which will cause the upper and lower sections to move with the elongate members and 60 intermediate section but will permit the same to have movement with relation thereto into and out of positions overlapping the intermediate section. In the particular construction illustrated the intermediate section 14, see Fig. 6, has mounted thereon near each end thereof a guide or pulley 36 about which extends a flexible member or chain 37 which is secured at one end to the adjacent arm 32 of the upper section 13 and at its lower end to the upper portion of the lower 65 section 15. In this manner the upper and lower sections are caused to move with the intermediate section when vertical movement is imparted to the latter and the upper and lower sections are caused to move simultaneously in opposite directions, movement imparted to either of these mem- 70

bers being transmitted through the chain 37 to the other member. This form of connection also serves as a counterbalancing connection between the upper and lower sections so that one will substantially counterbalance the weight of the other and the sections can be very easily moved from one position to another.

5 If the upper and lower gates are moved from their collapsed positions to their extended positions in a violent manner there is danger of the slide blocks being carried beyond the ends of the guides and to prevent such an occurrence I have provided means for positively limiting the movement of the upper and lower sections from their overlapping positions. In the form illustrated in Figs. 7 and 8 this means comprises a strap 38 secured to the lower section 15 near the upper edge thereof, extending about the lower edge of the intermediate section 14 and connected with the upper section near the lower edge thereof, 20 the strap being of such a length as to positively interrupt the movement of the sections before the guide blocks can move out of engagement with their guides. When the sections are in their collapsed and elevated positions an intermediate portion of the strap 38 will extend below the gate, see Figs. 2 and 7, and thus form a hand grip which may be grasped by the operator to lower the gate.

30 The operation of the gate will be readily understood from the foregoing description and it will be apparent that when the gate is in its normal or closed position the three sections thereof are arranged one above the other, as shown in Fig. 1. When the gate is to be opened the upper or lower section is moved toward its overlapping position with relation to the intermediate section, thereby causing the other movable section to be simultaneously moved toward its overlapping position. After the gate has been collapsed, or during the movement of the upper and lower sections to their overlapping positions, the intermediate section and therefore the gate as a whole is moved upwardly, so that the gate as a whole is moved in a collapsed condition into the space above the doorway 10, and because of the relatively narrow width of the gate when collapsed only a small clearance above the doorway is required to accommodate the same. Due to the construction and arrangement of the parts the operation of the gate may be very easily effected with but little effort on the part of the operator and there is little or no danger of the several parts being disarranged or broken so as to render the gate 40 inoperative.

45 While I have shown and described one embodiment of my invention I wish it to be understood that I do not desire to be limited to the details thereof as various modifications may occur to a 50 person skilled in the art.

Having now fully described my invention, what I claim as new and desire to secure by Letters Patent is:

55 1. A gate of the character described comprising an intermediate section, upper and lower sections, means for supporting said upper and lower sections on said intermediate section for simultaneous movement to or from positions overlapping said intermediate section, means 60 separate from and independent of said supporting means for connecting said upper and lower sections one to the other to positively limit their movements from said overlapping positions, and means for mounting the several sections for si- 65 70 75

multaneous movement toward or from an elevated position.

2. A gate of the character described comprising an intermediate section, upper and lower sections mounted for simultaneous movement to or from positions overlapping said intermediate section, a flexible member connected at one end with the upper portion of said lower section, extending about the lower edge of said intermediate section and connected at its other end with the lower portion of said upper section, and means for mounting the several sections for simultaneous movement toward or from an elevated position.

3. A gate of the character described comprising an intermediate section, upper and lower sections mounted for simultaneous movement to or from positions overlapping said intermediate section, a flexible member connected at one end with the upper portion of said lower section, extending about the lower edge of said intermediate section and connected at its other end with the lower portion of said upper section, and means for mounting the several sections for simultaneous movement toward or from an elevated position, said flexible member being arranged to extend below all of said sections and form a hand grip when said sections are in their overlapping positions.

4. A gate of the character described comprising a laterally spaced upright guides, elongate members connected with the respective guides for movement lengthwise thereof, an intermediate gate section arranged between and connected with said elongate members for movement therewith, and upper and lower gate sections connected with said elongate members for movement therewith and for movement with relation thereto into and out of positions overlapping said intermediate section.

5. A gate of the character described comprising laterally spaced upright guides, elongate members slidably supported on the respective guides, an intermediate gate section secured to said elongate members for movement therewith, a lower gate section slidably connected with said elongate members, an upper gate section having means at its upper portion for slidably connecting the same with said upright guides and having downwardly extending parts slidably connected with said elongate members, and means for connecting said upper and lower sections with said intermediate section for movement therewith and for movement with relation thereto.

6. A gate of the character described comprising laterally spaced upright guides, a gate section arranged between said upright guides and having at its ends supporting member provided with inclined guideways, and slide blocks engaging said upright guides and having parts movably mounted in the respective guideways of said supporting members.

7. A gate of the character described comprising laterally spaced upright guides, a gate section arranged between said guides, elongate members

secured to and spaced outwardly from the respective ends of said gate section and having parts slidably engaging said upright guides, each elongate member having flanges extending inwardly on opposite sides of said gate section, other gate sections arranged on opposite sides of the first mentioned section and having parts slidably engaging the respective flanges, and means for connecting the last mentioned gate sections with the first mentioned gate section for movement therewith and for movement with relation thereto into and out of positions overlapping said first mentioned gate section.

8. A gate of the character described comprising laterally spaced upright guides, a gate section arranged between said guides, elongate members secured to and spaced outwardly from the respective ends of said gate section and having parts slidably engaging said upright guides, each elongate member having at least one pair of supporting members provided with inclined slots, slide blocks movably mounted in the respective pairs of supporting members, having sliding engagement with said upright guides and having parts extending into said slots, each elongate member also having flanges extending inwardly on opposite sides of said gate section, other gate sections arranged on opposite sides of the first mentioned section and having parts slidably engaging the respective flanges, and means for connecting the last mentioned gate sections with the first mentioned gate section for movement therewith and for movement with relation thereto into and out of positions overlapping said first mentioned gate section.

9. A gate of the character described comprising laterally spaced upright guides, an intermediate gate section, means for connecting said gate section with said guides for movement lengthwise thereof, upper and lower gate sections, means carried by said intermediate section for movably supporting said upper and lower sections thereon in counterbalancing relation one to the other and to cause the same to move in unison with relation to said intermediate section, and means carried by said intermediate section to guide said upper and lower sections in their movement with relation to said intermediate section.

10. A gate of the character described comprising a single pair of laterally spaced guides, elongate members slidably supported on the respective guides, an intermediate gate section having a downwardly extending part at each end thereof, means for rigidly securing each elongate member to the adjacent end and downwardly extending part of said intermediate section, upper and lower gate sections slidably connected with said elongate members, and means for connecting said upper and lower sections with said intermediate sections for movement therewith and for movement with relation thereto into and out of positions overlapping said intermediate sections.

ARTHUR W. CUNNINGHAM.
